STRAIGHT BAR KNITTING MACHINES
AND METHOD

Michael Harrison, Ashby de la Zouch, and Alan Edward Hinckleff, Epperstone, England, assignors to William Cotton Limited

Filed June 13, 1961, Ser. No. 116,711

Claims priority, application Great Britain, June 14, 1960,
20,778/60

10 Claims. (Cl. 66—96)

This invention is for improvements in or relating to straight bar knitting machines of the Cotton's Patent and other similar type which are characterized by each having a row of bearded needles mounted on a bar for simultaneous operation, and a narrowing head for movements of loop transfer points in the transference of loops, the bar and narrowing head being operated through their own cam follower mechanism by cams on a cam shaft in the machine. The invention primarily concerns improvements in or modifications of the invention described in U.S. Patent No. 3,100,975 (Brown et al.) in which there is claimed a method of producing on a straight bar knitting machine employing bearded needles, knitted articles having a cable stitch pattern, in which method groups of loop transfer instruments are employed to pick up a group of loops from the bearded needles and to transfer them back to the needles with sub-groups of the loops crossed-over. There is also claimed in said specification a straight bar knitting machine, having means for producing knitted articles with cable stitch patterns, which means comprises bearded needles, adjacent sub-groups of loop transfer instruments for co-operation with the bearded needles, means mounting said instruments for dipping movements, means mounting said instruments for sideways movements in opposite directions appropriate for the transfer of loops by the instruments from some of the bearded needles to others of the bearded needles, and means for effecting said movements of the instruments appropriate to produce a crossed-over loop formation at spaced course intervals.

An object of the invention is to provide means whereby the cable stitch pattern is more clearly defined and preferably employing an improved transfer instrument control arrangement.

The invention provides an improvement in or a modification of the method claimed in our U.S. Patent No. 3,100,975 which consists in causing a needle at each side of the cable stitch forming needles to release their loops for a number of courses during which the cable stitch is formed thereby producing a repetitive drop stitch at each side of the cable stitch. Conveniently at the commencement of making the cable stitch, the loops last formed before the drop stitches are locked in the fabric against running.

The invention also provides an improvement in or a modification of the machine claimed in our U.S. Patent No. 3,100,975 which comprises means operably associated with a needle at each side of the cable stitch forming needles for causing each said needle to release their loops, and means for causing repetition of this for a number of courses during which the cable stitch is formed, thereby producing a repetitive drop stitch at each side of the cable stitch.

Conveniently, there is also provided means for operating the sub-groups of instruments in the last course before the drop stitches are formed, to lock the loop of each said needle in the fabric against running.

For making the drop stitches there may be provided a bent-over tipped point operably associated with the sub-groups of transfer instruments at each side thereof, to close their associated needle beards and allow the latter's loops to be cast off.

2

For locking each of the aforesaid loops, the sub-groups of transfer instruments may be operated by suitable means to transfer each of said loops to adjacent needles. Conveniently, these means consist of a cam shaft, cam-operated mechanism, and racked cam mechanism for obtaining appropriate dipping and sideways movements of

The sequence of movements of the sub-groups of the sub-groups of transfer instruments.

transfer instruments may be first to pick up and transfer loops, including the loop from one of the side needles and excluding the loop on the other side needle, to next adjacent needles in a direction towards said other side needle, then to pick-up and transfer loops, including the loop from the latter side needle and excluding the loop transferred from the one side needle to next adjacent needles in the opposite direction.

There is further provided means for displacing the sub-groups of transfer instruments into and out of operative position, which means may include for manual and automatic displacements respectively.

The above and other features of the invention set out in the appended claims are incorporated in the construction which will now be described as a specific embodiment with reference to the accompanying drawings in which:

FIGURE 37 is a pictorial view of part of the fabric produced.

Referring to FIGURE 1, a Cotton's Patent or other similar straight bar knitting machine is represented by bearded needles 1 which are mounted for simultaneous operation on a needle bar 2 (shown particularly in FIGURE 4) operated through cam follower mechanism such as 3 by rotary cams such as a presser course cam 4 on the machine's main cam shaft 5, and a narrowing head represented generally at 6 which is operated through cam follower mechanism 7 (shown particularly in FIGURE 5) by a shaped narrowing head fashioning cam 8 on the machine's cam shaft 5.

Usual cam shaft shogging mechanism (shown particularly in FIGURES 7 to 9) comprises usual rotary cam 12 (with usual rise not seen in the views FIGURES 7, 8) on the cam shaft 5 and having opposite face cams 13, 14, a cam follower 15 for cam 12 and which is connected by usual mechanism 16 including bellcrank arms 16c to 16f connected with a double-armed lever 16a pivoted on a pivot 16b and carrying a pair of cam followers 17, 18 for engagement respectively by the face cams 13, 14. The parts 16 represent the usual bell crank lever, link, and straight lever mechanism whereof the straight lever which mounts the cam followers 17, 18, is connected by the link to one end of the bell crank lever, and the other end of the bell crank lever is connected to a plunger 19 (i.e., a rod spring biased in a cylinder) having a collar 20, and for removable engagement behind the collar 20 there is a lever 21 operated through a lever 22 and spring 22a by single or double bits 23, 24 on the machine's pattern chain 25.

The usual arrangement is that when a single bit 23 operates lever 22 (FIGURE 9), lever 21 is thereby removed from behind the collar 20 so that the plunger 19 is free to spring away, i.e., toward the cam 12) so that the cam follower 15 can then ride up and down the rise on the cam 12 and through the consequent pivoting of the bell crank lever this causes the cam followers 17, 18 to be brought alternately into the path of the cams 13,

14 respectively. FIGURE 8 shows the position where the cam follower 15 has moved down the rise on the cam 12, the cam follower 18 has consequently lowered, and cam follower 17 has been raised for engagement by the face cam 13 whereby the cam shaft 5 will be shogged to the right. When the rise on cam 12 next engages the cam follower, this reverses the cam followers 17, 18 and the cam shaft is shogged to the left. Each movement is made at required times; and to carry one set of cams away from their cam followers and to engage different cams with the cam followers. Cam 12 turns one arm 16c of the bellcrank so that its other perpendicular arms 16e, 16f move the end of lever 16a which turns about pivot 16b and moves cam follower 18 into engagement with face cam 18, while cam follower 17 moves away from face cam 13. Spring means, not shown, bias the cam followers toward the cams so that plunger 19 is restored by the cam 12 to its initial position. A particular result of this shogging of the cam shaft 5 to the right by face cam 13 is to put the machine into a fashioning motion by the shaped narrowing head fashioning cam 8 (FIGURE 5) becoming operative from a circular narrowing head course cam 8a such that the narrowing head 6 then has a motion constituted by a first dip, next a part rise, and then a second dip followed by a complete rise back to its original position, the usual object of this being to cause loop transfer points such as 26 of a fashioning finger 26a (FIGURE 2) to transfer loops from some needles to others at selvedges "S" of the fabric "F" for fashioning by widening or narrowing. In the instance of the single bit 23, the next rack of the chain 25 displaces it from the lever 22 and the cam 12 not only reverses the cam followers 17, 18 so that the cam shaft is shogged back to the left by face cam 14 but the plunger 19 is returned to its original position by the rise on cam 12 projected so that the lever 21 falls in behind the collar 20 to terminate the shogging motion. In the instance of the double bit 24, this causes the lever 21 to be held clear of the collar 20 so that two shogging or fashioning motions involving two revolutions of the main cam shaft occur consecutively.

In the needle mechanism there is provided a circular course cam 27 (particularly FIGURE 4) which is rendered operative by shogging of a movable cam follower 28 on to it from the cam 4 and prevents the beards 1a of the needles 1 from being pressed when required (for a purpose hereinafter referred to). The shogging of the cam follower 28 is effected by a fork 29 operated through suitable mechanism 29a from the machines pattern chain 25.

The narrowing head 6 (see particularly FIGURE 2) generally incorporates transfer point bars 30, 31, 32, 33 slidably mounted in spaced brackets 34, 35 carried by arcuate arms 36, 36a, the latter being mounted on a shaft 37 for pivotal movement.

In addition the bracket 35 has a forward extension 35a in which there is slidably mounted a pair of bars 38, 39 to which there is secured what may be called for convenience a transfer unit or cable box 40, and which is raised and lowered by raising and lowering of the narrowing head.

This cable box 40 (see also FIGURE 3) consists of an inverted "L" shaped block of channel section having a rear cover 41 and an upper recess 40a for the bars 38, 39 and which is bridged by a top cover 41a. Slidably mounted in the cable box 40 there are two cable or transfer fingers 42, 43 each having three downwardly projecting loop transfer points 42P, 43P. This slidable mounting allows for the cable fingers 42, 43 to be raised and lowered by the raising and lowering of the cable box 40 with the narrowing head, and in addition, the fingers have some independent movement. More specifically the cable finger 43 is vertically displaceable, by means to be described, in either direction from standing position in transfer unit or the cable box 40, whereas

cable finger 42 is only displaceable, by means to be described, above standing position because of a pin 44 (particularly FIGURE 3) on the finger 42 projecting over a shoulder 43b of the cable finger 43 for raising the cable finger 43 and consequently the finger 42, through the shoulder 43b and the pin 44, and independently of the cable box, and for lowering finger 43 independently of finger 42 and of the cable box 40.

Cable finger 43 has an upper hook 43a which hooks onto an operating rod 45 constituting an operating means for the transfer finger 43. Hook 43a has an attached prop 43b for displaceable engagement over a rod 46 and a gap "G" for displaceable disengagement from an elongated operating rod 45.

The cable fingers 42, 43 are of channel form and they have slidably mounted in them respectively drop stitch slides or fingers 47 and 48 which have forks 47a and 48a engaging said rod 46, the forks being sufficiently long to remain in continual engagement with rod 46, and the slides each carrying a downwardly projecting drop-stitch point 47P, 48P.

The elongated operating member or rod 46 is carried by arms 49, 50 (FIGURE 2) which are secured on an elongated rocking support spindle 51 and, as shown in FIGS. 1 and 2a, the latter is rocked by a cam 56 through an arm 51a, link connections 52, 53 a cam follower 54 (FIGURE 2a) and spring 55. The drop stitch course cam 56 on the main shaft 5 is operable in the normal knitting motion of the machine. A circular drop stitch fashioning cam 56a is moved under the cam follower 54 by the shogging of the cam shaft 5 for the fashioning motion. Elements 46, 49, 50, 51, 52, 53, 54, 55, 56 are the operating means of the drop stitch fingers 47, 48. A manually releasable latch 51b (FIGURE 1) on a pivot carried by link 52 and connecting the arm 51a to the link 52 by peg and slot 51c is operable to render the spindle 51 and consequently the drop stitch points operative and inoperative.

The rod 45 is carried by arms 57, 58 secured to rocking spindle 59, the latter being rocked through arm 60, link 61, cam follower means 62 (FIGURE 2a) including cam follower 62a and a transfer point fashioning cam 63 on the cam shaft 5. The cam follower 62a is shiftable, by fork 62b and suitable mechanism 62c from the pattern chain 25, from said cam 63 (which is operable during certain fashioning motions) either onto a transfer point circular fashioning cam 63a for other fashioning motions or onto a transfer point circular course cam 63b for normal knitting motions of the machine, a suitable change between the cams also being made when the cam shaft shogs.

For sideways displacement of the cable box 40, the bar 38 (FIGURE 2) is operative, i.e., for driving a left hand cable box for right over left cable stitch, (the other bar 39 is for driving a right hand cable box, i.e., for left over right cable stitch) by having formed in cable box 40 an upper slot 41a connected with the lower channel 40c of cable box 40 and having a block 38a partly disposed in channel 40c and partly in slot 41a. A bar 38 extends through an upper recess in block 38a and is clamped to the same by a cap 38c secured to block 38 by screws 38b. The bars 38, 39 are shogged endwise by first operating means including lock stitch and cable stitch Dawson wheels 64, 65, 66, 67 (FIGURE 2). For this purpose cam followers 68, 69 which are on a rod 70a, 71a carried by brackets 70b, 71b which are secured to the bars 38, 39 and the cam followers are displaceable by hand turned screws 70, 71, into engagement with appropriate of the cams. The cams are racked round by ratchet wheel 72, clawker 73, bell crank lever 74 and link connection 75 to cam follower means 76 (FIGS. 1 and 2a) including a cam follower 76a. The latter is shiftable, for example by hand or by fork 76b through suitable mechanism 76c from the pattern chain 25, to engage either a lock stitch shaped fashioning cam 77 or a lock

stitch differently shaped fashioning cam 77a, in the fashioning motion of the machine, or a lock stitch circular course cam 77b, in the normal knitting cycle of the machine. These cams are on the main cam shaft 5 (see also FIGURE 6), a suitable change between the cams being also effected when the cam shaft shogs. Second operating means including cam shaft 5 raise and lower transfer unit 40 with head 6.

As allowed by the aforesaid slots 40c, 41a (FIGURE 3) and recess 40a, the cable box 40 is displaceable up to the fashioning finger bars 30, 31, 32, 33 into operative position against return bias of a spring 78, and it is there releasably held by a latch 79 engaging behind a lug 80 under bias of a spring 81 and constituting a releasable latching means. A knob 40b on the cable box 40 facilitates handling of the box.

When it is required to render the cable box inoperative (for a purpose to be described or to allow passage of a fashioning finger such as 26) a rotary cam 82 (FIG. 2) 20 on a shaft 83 immediately above the box is automatically operated to engage a peg 79a (FIG. 3) on latch 79 and release the latter from the lug 80, so that spring 78 returns the cable box 40 to its inoperative position shown in FIGURE 2 spaced forwardly from the fashioning finger bars 30, 31, 32, 33. The shaft 83 is rotated for said purpose by any suitable means. For example the shaft 83 which is shown cut away to the left of the cam 82, is rotated through pawl and ratchet means 84 (FIG. 2), with indexing mechanism 85, operable through link 30 86, cam follower means 87 (FIGS. 1 and 2a) with cam follower 87a shiftable by fork 87b through suitable means 87c from the chain 25, and a cable box shaped course cam 88 on the cam shaft 5 or for example by upward motion of the narrowing machine. Cable box 35 circular cams 88a and 88b are also provided either of which may be operative on cam follower 87a, a suitable change between the cams also being effected when the cam shaft shogs.

In this position of the parts the prop 43b of the hook 40 43a rests on the rocking rod 46 (with the hook 43a clear of rod 45) so that in subsequent fashionings, when rod 46 and consequently the drop stitch points are raised and held by fashioning cams, cable stitch finger 43, and finger 42 (by means of said shoulder 43b and pin 44) are lifted clear of the fabric. After fashioning, when rod 46 and the drop stitch points are lowered the fingers 42, 43 return to starting height under bias of a spring 89 which as shown in FIGURE 3 is connected to the front of the cable box 40 and to the finger 42 through a slot in the box 40 (the finger 42 being lowered directly by the spring and the finger 43 being lowered by the spring through the medium of the shoulder 43b and the pin 44), thus allowing the cable box 40 to be re-engaged to operational position when required against bias of the spring 78.

A multiple number of cable boxes, either right hand or left hand or both, may be mounted on the bars 38, 39 and each is capable of being disengaged automatically in said manner and independently of the others at any pre-set time, any number of either hand of cable boxes 55 60 being in operation simultaneously.

The drop-stitch points 47P, 48P have channels 90, 91 and tips 92, 93 bent in opposite direction to the tips of the transfer points 42P, 43P for a purpose to be described.

On the machine as above described there can be produced a cable stitch patterned fabric with drop stitches at each side of the cable stitches as shown in the fabric FIGURES 35, 36.

The complete method of operation for this purpose is as follows with reference firstly to the stage shown in FIGURE 10.

At this stage which follows production of a suitable length of knitted fabric (with the hand latch 51b disconnected and the drop stitch points being held up by a

spring not shown) the transfer points 42P, 43P and drop-stitch points 47P, 48P, are located by pulsing-in of the cable box 40 in operative position over the needles 1: the narrowing head 6 is inoperative and the transfer point circular cam 63b is operative so that all the points are at raised height with the drop-stitch points higher than the transfer points (which are at the same height as the selvedge fashioning points such as 26) and the latter over needles with which they subsequently cooperate to form cable stitches.

The first general operation required is to transfer loops from needles which are to thereafter drop stitches so that the fabric does not unrove past the starting course. For this purpose first the cam follower 69 is displaced onto lockstitch Dawson wheel 64. The ensuing description of operations will be appropriate to the use of one cable box 40 and a cable stitch of one hand, it being understood that other cable boxes if provided are similarly operated if of the same hand, and oppositely operated if of the other hand using the bar 39, cam follower 68 and cams 66, 67 in similar manner to cams 64, 65 for the cable box 40 and bar 38.

A double bit 24 on the pattern chain 25 becomes operative by a rack of the chain 25 to put the machine into a double fashioning motion by which lock stitch shaped cam 77 becomes operative, and by ensuing rotation of cam 77 Dawson wheel 64 is racked around at a suitable frequency. The effect of introducing Dawson wheel 64 racked at same frequency is to cause sideways displacement of the cable box 40 to the left in FIGURE 10 to the extent of one needle spacing indicated by the arrow to the position shown in full lines in FIGURE 11. In addition, by the ensuing first dip of the narrowing head 6 and rotation of the circular cam 63a the transfer points are lowered to box with the needles as indicated in broken lines in FIGURE 11. At this stage, i.e., during a fashioning motion of the machine the drop stitch shaped course cam 56 is ineffective.

At the stage of FIGURE 12 the needles 1 are also lowered (by their usual needle lowering cam as well known in the art) with the continued lowering of the transfer points so that six needle loops NL are landed onto the transfer points. In the following rise of the narrowing head, the transfer points take off the needle loops NL from the needles 1 as shown in FIGURE 13, and following this operation of the Dawson wheel 64 causes sideways displacement of the transfer points one needle spacing to the right as in FIGURE 14. In the second dip of the narrowing head 6, FIGURE 15, the transfer points are boxed with the six needles then opposite them followed by the last rise of the narrowing head in the first fashioning motion by which the loops NL are relinquished by the transfer points to the latter six needles, FIGURE 16, thereby leaving one needle 1b empty.

FIGURE 17 shows the next step whereat the lock stitch Dawson wheel 64 has caused sideways displacement of the transfer points one needle spacing to the right, and it also shows the points in broken lines boxed with the needles as a result of the first dip of the narrowing head in the second fashioning motion. FIGURE 18 shows the usual lowering of needles with the transfer points to land the loops NL on the points, and FIGURE 19 shows the result of the first rise of the second fashioning motion which is for the points to take off the loops NL from the needles.

The Dawson wheel 64 then causes sideways displacement of the points one needle spacing to the left, FIGURE 20, followed by re-boxing of the points with needles, FIGURE 21, as a result of the second dip of the narrowing head in the second fashioning motion, so that needle 1c is empty.

In FIGURE 22 the last rise of the narrowing head has caused complete raising of the points leaving the loops on the needles with said needles 1b, 1c empty and their loops transferred to other needles by which they are

locked in the desired manner against subsequent unroving.

Thereafter, with the hand latch 51b re-connected, a number of courses of knitted loops may be made with the narrowing head out of action by a rack of the chain 5 25 advancing the bit 24 to inoperative position and the cam shaft shogged back to put the machine into a normal knitting motion. An effect of this is to render the drop stitch shaped course cam 56 operative whereby immediately following the production of each course, in which 10 needles 1b, 1c (FIGURE 23) receive yarn without knitting it, the drop stitch points 47P, 48P are lowered, FIGURE 24, to box with the needles 1b, 1c. This is followed by the needles lowering in usual manner with the further lowering points, FIG. 25, and by virtue 15 of the tips of the points being bent away from the needles, the lower ends of the closed beards are exposed so that the yarn on needles 1b, 1c is landed onto their beards. Consequently, when the needles continue lowering, which is accompanied by the drop stitch shaped course cam 20 56 raising the drop stitch points, FIGURE 26, the yarn which was on needles 1b, 1c is dropped off them forming a drop stitch D, D1.

This sequence of knitting courses and dropping stitches can be repeated as required such as for three courses 25 as shown in FIGURE 27 until it is required to start forming a cable stitch whereupon a double bit 24 on the pattern chain 25 puts the machine into a double fashioning motion with similar effects as before with exceptions that lockstitch shaped cam 77a is operative by operation 30 of fork 76b from the pattern chain so that the sideways displacements of the transfer points is different.

More specifically FIGURE 27 shows the effect of the first dip of the narrowing head which is for the transfer points to box with the six needles between the drop stitch 35 needles 1b, 1c. The following part rise of the narrowing head causes the transfer points FIGURE 28 to take off the loops from the needles.

Following the formation of the anteroval area, the follower 69 is manually removed from operable contact 40 with Dawson wheel 64 by means of screw 71, and in preparation for the cable stitching, the cam follower 69 is displaced onto Dawson wheel 65 by means of screw 71. This now causes, by cam 77a racking the Dawson wheel 65 at suitable frequency, sideways displacement of the transfer points to the right, FIGURE 29, a distance of 45 three needle spacings. The second dip of the narrowing head and the second operating means 45 and 57 to 63 to lower 43 causes boxing of the transfer points with the needles then opposite them FIGURE 30, and at about 50 this stage chain 25 racks to shift cam follower 62a onto the cam 63 by a pattern bit. The last rise of the narrowing head FIGURE 31 in the first fashioning motion then causes raising of the block 38 complete raising of the group of three left hand transfer points 42P to leave their group of loops L3 transferred to the right onto their then 55 associated group of needles, the group of three right hand transfer points 43 remaining at a low height by the operation of the transfer point shaped cam 63 so that this latter group of three points retain the group of loops R3. During the same rack of the chain the needle 60 presser cam follower 28, FIGURE 4, is shogged by a pattern bit and fork 29 onto cam 27 whereby following the needles usual movement forwardly away from the transfer points, the needles are prevented from closing their beards against the transfer points 42P so that in the first dip 65 (FIGURE 32) and part rise (FIGURE 33) of the second narrowing motion none of the transfer points take off any needle loops from their then associated group of needles but the group of right hand transfer points 43P retain the group of loops R3, FIGURE 33. It is to be noted that the group of three needles to which loops L3 have been transferred to the right are those from which loops R3 have been removed by the group of three right hand transfer points 43P.

The Dawson wheel 65 then causes sideways displacement of the transfer points a distance of six needle

spacings to the left, FIGURE 34, and, in the second dip and final rise of the narrowing head in the second fashioning motion, the three right hand transfer points 43P are boxed with their then associated needles followed by lowering together of the points and needles so that the three loops R3 are transferred to those three needles from which loops had been removed by the three left hand transfer points 42P, FIGURE 35. In this FIGURE 35 needles are shown in broken lines in their next usual raised position ready for the next course.

The next rack of the chain 25 advances the pattern bits so that the machine changes to a knitting motion with similar effects as before resulting in a plain knitted course being produced with drop stitches on needles 1b, 1c, this being repeated say for about seven courses as at 7C in FIGURE 36 followed by a repeat cable stitch as shown and so on.

The pictorial view of the fabric, FIGURE 37, shows how the provision of the drop stitches at each side of the cable stitching renders the cable stitching clearly defined with particularly pleasing effect.

What we claim is:

1. A straight bar knitting machine having, in combination, a row of needles having beards, supporting means, a transfer unit carried by said supporting means, first operating means for moving said transfer unit in opposite directions along the row of needles, second operating means for raising and lowering said transfer unit, transfer fingers slidably mounted in said transfer unit and movable therewith, third operating means for raising and lowering said transfer fingers independently of each other and of said transfer unit, sets of transfer points carried by said transfer fingers and movable thereby and by said transfer unit to cooperate with a group of the needles and form thereon a succession of cable stitches, drop stitch fingers slidably mounted in said transfer unit at the outer sides of said transfer fingers and movable with said transfer unit, fourth operating means for raising and lowering said drop stitch fingers independently of said transfer fingers and of said transfer unit, and drop stitch points carried by said drop stitch fingers and movable thereby and by said transfer unit to cooperate with the spaced needles adjacent the outer sides of said group of needles and cast off the loops from these spaced needles course by course to form successions of drop stitches continuously along the outer sides of the succession of cable stitches.

2. A machine as claimed in claim 1, having releasable latching means in said fourth operating means operable for rendering said drop stitch fingers and points operative and inoperative.

3. A machine as claimed in claim 1 having fork connections on the upper ends of said drop stitch fingers, and an elongated member in said fourth operating means with which said fork connections engage and along which they can slide for raising and lowering of the drop stitch fingers in any position of their lateral movement by said transfer unit.

4. A machine as claimed in claim 1 having longitudinal slots in the outer sides of said transfer fingers for slidably mounting said drop stitch fingers.

5. A machine as claimed in claim 2 wherein said fourth operating means comprises an elongated rockable support, first and second spaced arms on said support, an elongated operating member carried by said arms and with which said drop stitch fingers have sliding connections, a third arm on said support, cam operating mechanism, a link connection between said third arm and said cam operating mechanism, and a releasable latch connection between said link and said third arm.

6. A machine as claimed in claim 5 having a prop portion on one of said transfer fingers for engagement by said elongated operating member in a movement of the latter to raise all the fingers to inoperative height.

7. A straight bar knitting machine having, in combination, a row of needles having beards, a narrowing

head, a supporting means, first operating means for moving said supporting means to and fro parallel to the row of needles, a transfer unit carried by said supporting means for movement therewith and slidable for movement transversely therefor, side by side transfer fingers slidable in said transfer unit, overlapping abutments on said transfer fingers, a hook connection and a prop on one of said transfer fingers, second operating means including a first elongated operating member for engagement with said hook connections, drop stitch fingers slidably in said transfer unit at the outer sides of said transfer fingers, fork connections on said drop stitch fingers, third operating means including a second elongated operating member for engagement with said fork connections, spring means biasing said transfer unit outwardly, a releasable latching device for releasably latching said transfer unit to said supporting means when the unit is pushed inwards into operative position in which said hook connection is engaged by said first elongated operating member and said prop is clear of said second elongated operating member, and cam operating means operable on said releasable latching means to release the latching connection between said transfer unit and said supporting means allowing the transfer unit to spring outwards by said spring means to inoperative position in which said hook connection is clear of said first elongated operating member and said prop overlies said second elongated operating member.

8. In a straight bar knitting machine the combination 30 with needles, a transfer unit, transfer fingers carried by said transfer unit permanently side by side, and first operating means operably associated with said transfer unit and transfer fingers for causing the latter to cooperate with the needles to form cable stitches, of drop stitch 35 points slidable in said transfer unit at the outer sides of said transfer fingers, and second operating means operatively associated with said drop stitch points for causing the drop stitch points to cooperate with the needles to form drop stitches at the outer sides of the cable stitches.

9. A straight bar knitting machine having, in combination, a row of needles, needle actuating means associated with said row of needles having beards and operably arranged for the needles to produce successive courses of knitted loop stitches, a loop transfer unit associated with 45 a group of said needles, transfer actuating means associated with said loop transfer unit and operably arranged for said loop transfer unit to cooperate with said group of needles in spaced courses and form crossed over stitch loops in said spaced courses for cable stitch patterning 50 in a predetermined number of courses, drop stitch elements carried by said loop transfer unit at the sides thereof and associated with spaced needles at the outer sides of said group of needles, and drop stitch actuating means associated with said drop stitch elements and operably arranged for operation of said drop stitch elements 55 once in each of said predetermined number of courses for those stitch loops which are formed on said spaced needles to be dropped off their needles in every one of said predetermined number of courses.

10. A method for producing knitted articles with a 60 succession of cable stitches consisting of crossed over stitches and plain courses on a knitting machine having needles with beards, comprising first steps in a course of picking up first and second groups of loops from staggered first and second groups of needles having beards; placing said first group of loops on said second group of needles and said second group of loops on said first group of needles, so that crossed stitches are formed while predetermined needles at the ends of said groups 65 of needles remain without loops; next knitting a plurality of plain courses, then repeating said first steps in the next course; and second steps of supplying a new yarn to said bearded needles, and closing the beards of said predetermined needles while lowering said needles 70 for dropping the yarn off said predetermined needles, so

11

that a drop stitch is formed on each side of said crossed stitches; and repeating said second steps once in each of said courses, so that successions of positively made drop stitches are disposed along the sides of the crossed stitches and of the plain courses.
